UNITED STATES PATENT OFFICE.

FRANCIS W. COOPER AND HENRY STEADWORTHY, OF MONTREAL, QUEBEC, CANADA.

ANCHOR AND CLIP FOR RAILS AND THE LIKE.

1,422,340.

Specification of Letters Patent.

Patented July 11, 1922.

Application filed December 1, 1921. Serial No. 519,201.

To all whom it may concern:

Be it known that we, FRANCIS W. COOPER and HENRY STEADWORTHY, both subjects of the King of Great Britain, and residents of 5 the city of Montreal, in the Province of Quebec, and Dominion of Canada, have invented certain new and useful Improvements in Anchors and Clips for Rails and the like, of which the following is a full, 10 clear, and exact description.

This invention relates to improvements in anchors or clips to hold a rail, frog or the like to a base plate, rail plate or other structure.

15 The primary object is to provide an anchor or clip applicable to a standard tie plate to connect a rail thereto and tend to hold the rail against longitudinal movement relatively to the plate.

20 A further object is to provide a device which will not become loosened by vibration nor by wave movement of the rail due to a train moving thereover.

25 A still further object is to provide a device a simple form, small size and light weight which may be easily and cheaply manufactured and sold at low cost.

30 Another object is to provide a device which may be easily assembled on or removed from a rail, but which will be substantially proof against removal by an accidental blow.

35 Still another object is to provide a device which may be assembled apart from a rail or plate without foreign connecting means, so as to be handled as a unit in transport and distribution and which may be easily and quickly taken apart for application to a rail.

40 An additional object is to provide a device which may be attached without the use of special tools other than those ordinarily used in track laying.

45 One more object is to provide a device which is applicable without adjustment to practically all sizes of rails or at least to a very wide range of sizes.

50 The invention comprises a resilient plate or clip of any suitable form adapted to bear downwardly on the base of a rail and on the plate carrying the rail, a hook member to engage both the clip and the rail supporting plate, and an adjustable key to secure the hook and clip together.

In the following description and accompanying drawings, the invention is described and shown only in connection with a rail and a tie plate but it will be understood that this is purely for purposes of explanation and is in no way limitative, as the invention has a much wider application.

In the drawings which illustrate the application of the invention to a rail and tie plate;—

Fig. 1 is an end elevation.

Fig. 2 is a side elevation.

Fig. 3 is a plan view of the anchor in position.

Fig. 4 is a bottom plan view of the clip plate alone.

Fig. 5 is an end elevation of an alternative form.

Fig. 6 is a side elevation of the form shown in Figure 5.

Referring more particularly to the drawings, 11 designates a tie plate of any suitable pattern provided with holes 12 for the passage of spikes 13 to secure the plate to a tie and also to hold the rail down on the plate.

According to the present invention, the 80 anchor or clip comprises a plate or strip 14 of spring steel bent intermediate its ends, as at 15, roughly to U-shape, to provide a long arm 16 and a short arm 17. The end of the clip in the arm 17 is notched out intermediate the side edges providing an opening 18 and the metal displaced in forming this notch is turned away from the arm 16 to form a tongue 19 substantially normal to the arm 17. The arm 16 is provided with 90 an opening 20, the innermost edge of which substantially aligns with the bottom of the notch 18. The clip arm 16 is not necessarily straight but may be provided with a slight initial curvature located preferably midway 95 between the inner and outer edges of the notch 20, as clearly shown in Figure 1.

The short arm 17 of the clip plate is adapted to lie upon a tie plate, with the tongue 19 depending through a spike hole 100 of the plate, and the end portion of the arm 16 is adapted to lie upon the upper surface of a rail base.

In order to secure the plate 14 in position, a double hook member 21 is provided having 105 at one end a spear-shaped end portion 22 having what may be termed barbs 23 and 24, the former adapted for engagement with

the lower surface of the tie plate and the latter with the lower extremity of the tongue 19. The body of the member 21 is of such thickness that when lying close against 5 the tongue 19, the two will just fill a spike hole 12. The body of the hook member passes through the inner portion of the opening 20 in a substantially vertical direction and is then turned upon itself at 10 25 to provide a depending arm or hook 26, the extremity of which passes through the outer portion of the opening 20 and into or substantially into engagement with the upper surface of a rail base. The tongue 19 and 15 hook member 21 are of such width that they completely fill the spike hole 12. It will be observed that the barb or hook 23 projects a considerable distance under the tie plate and so obtains a very good grip, the security 20 of which is assured by the tongue 19 filling the spike hole and preventing the hook member backing away from the plate.

The hook and clip are connected and held 25 in place by a wedge-shaped key 27, both long edges of which are rounded transversely of the key, as will be clearly seen in Figure 1. The upper edge of the key is provided with a plurality of uniformly spaced shallow notches 28, which co-operate with the 30 slight curvature of the member 21 at the bend 25 in the driving direction of the key, which curvature it is well understood will follow naturally from the bending of the member 21 or which may be specially provided 35 during the formation of the bend 25.

The modified form of the invention shown in Figures 5 and 6 differs from the form already described chiefly in the shape of the clip member. The long arm of this member, 40 designated 16^a, is substantially the same as in the previously described form but the short arm 17^a, instead of lying approximately parallel with the long arm, is disposed approximately at right angles thereto 45 and is in end abutting relation with the tie plate. Owing to the different disposition of the arm 17^a, there can be no tongue to hold the hook member in position. This is effected by means of a special spike 19^a driven 50 through the hole 12 in the plate outside the hook member. The hook member itself is of the same form as previously described, except that it lacks the second bar 24. The key is exactly the same as previously 55 described. In the event that it is desired to provide a special tie plate and to use a standard spike in place of the spike 19^a, the arm 17^a may be bifurcated at its end, as at 29, to make provision for the spike head, 60 unless of course the arm 17^a is positioned a sufficient distance from the spike hole to give clearance for the spike head.

The application of the device is extremely 65 simple. A tie plate and rail being in position, the hook member is driven down

through the selected spike hole until the extremity of the hook 26 engages or substantially engages the top of the rail base. The sharpened point of the member makes this driving a very easy matter. The hook member is now moved toward the rail, so as to engage the barb or hook 23 thereof under the tie plate. This movement is effected by driving a spike into the spike hole on the opposite side of the hook member from the 70 rail. The inclined surface of the hook 23 forces the same up against the tie plate during the lateral movement. In the case of the construction shown in Figure 1, an ordinary track spike afterwards removed, will serve, 75 while in the form shown in Figure 5, the permanent special spike 19^a or a permanent standard spike replacing it will serve to move the hook member as desired. The clip plate is now dropped over the hook 80 member, so that it bears at one end on the top of the rail base and at the opposite end on the tie plate at each side of the spike hole. In the form shown in Figure 1, the tongue 19 drops into the spike hole outside 85 the hook member and holds the hook member in position, the chamfer 29 on the end of the tongue facilitating its insertion and eliminating any downwardly presented surface which might bear against a tie and 90 resist downward movement of the clip. In the case of the form shown in Figure 1, the relation of the arms 16 and 17 to one another is preferably such that the bearing above 95 mentioned is at the extreme ends of the 100 arms, while in the form shown in Figure 5, the bearing is preferably at the extreme end of the arm 16^a. In other words, these bearings are preferably at the outset line bearings owing to the angular relation of the 105 arms and the surfaces which they engage. The key is now inserted small end first between the bend or loop 25 and the plate and with its notched edge remote from the plate. The key is now driven as tightly as desired 110 and, by the wedging action which it exerts, presses down on the clip plate and draws up on the hook member. This pressing down of the plate flexes the same, so that it obtains a substantial surface bearing 115 on the rail base at the extremity of the long arm and, in the case of the form shown in Figure 1, an equally substantial bearing on the tie plate at the extremity of its short arm. It will readily be seen that in this 120 tightening action, substantially the whole length of the plate is flexed and is active as a spring. The upward pull on the hook member draws its barb 23 very tightly 125 against the under surface of the tie plate.

The operation of the device as a clip or anchor is as follows:—The downward pressure of the clip holds the same very tightly to the rail and at the same time holds the rail down on the tie plate, while the hook 130

member holds the clip to the tie plate. The resilient nature of the clip, which permits it to flex slightly, avoids breakage due to vibration, sudden shocks or wave motion in the rail and, by reason of this resiliency, the clip remains always in tight engagement with the rail. The hook member holds the clip against movement relatively to the tie plate in the longitudinal direction of the rail and the frictional engagement between the clip and rail tends to hold the rail against the longitudinal movement imparted to it by a moving train or from other causes. When the key is driven tight, the tongue 19 or the spike 19^a holds the barb 23 against backing away from and disengaging the tie plate, while at the same time the engagement of the hook 26 in the clip opening 20 prevents the hook from being opened by the tension. If the clip should break, the extremity of this hook 26 will constitute a holding down member for the rail and the hook member a connection between the rail and tie plate. The head 22 of the hook member is prevented from bending or tipping with consequent tendency to disengage its barb 23 from the tie plate, by reason of the engagement of the barb 24 under the tongue 19. This engagement also provides for the tensioning or flexing of the clip plate between the two ends of the hook member, so that the device may be assembled and handled as a unit in transportation and distribution. The notches on the upper edge of the key serve to hold the key against backing out and also serve as a guide to indicate how far the key should be driven for different sizes of rails. The resiliency of the clip plate renders the device adjustable to a wide range of rail sizes, so that the device may be used on practically any size of rail in general use. Preferably, however, with a view to securing the best results, the device will be made in a variety of sizes. The difference in the device for different sizes of rails may be confined to the key member 27 but, if unusually thin or thick plates are used under the rail, it will of course be necessary to provide a special hook member but, under ordinary circumstances, the hook member may be standard for all sizes. It will be understood, however, that the variation may be effected in other ways. The advantages of the device are numerous and will be manifest to anyone skilled in the art. It will be apparent that the load is disposed symmetrically and equally on both sides of the spike hole, so that the hook member is supported on both sides by the clip plate and is not liable to displacement by a chance blow in the line of the rail or by the driving of the key. The device provides a connection between a rail or the like and plate thereunder which is rigid for all practical purposes but which yet has sufficient resiliency to accommodate itself to wear and to withstand sudden shocks and vibration without fracture. The device may be applied to existing construction quite as easily as to new construction. The device when applied on the inside of a rail will replace one of the spikes, as it holds the rail so securely to the plate that the plate becomes substantially a part of the base and the centre of oscillation is moved from the outside edge of the rail base to the outside edge of the plate, with the obvious result that a great additional upsetting force is necessary to tilt the rail outwardly.

While the invention has been shown and described as embodied in a construction in which the hook member turns inwardly at the top and bottom to overhang the rail base and underlie the rail support beneath the rail and in which the hook member passes through the plate, it will be understood that, while this arrangement is preferable, it is not essential and therefore that the invention contemplates the disposition of the hook member otherwise than passing through the plate and also the turning of the hooks otherwise than shown. The clip or anchor has been illustrated as applied on the inner side of a rail but this is not obligatory and the clip may be used on the outer side if desired. Furthermore, while the device has been designed primarily for use as a rail anchor or clip, its use is not thus limited but the device may be applied to many other things where either temporary or quick release fastenings are required between any two objects which may be connected by a device of this construction.

Having thus described our invention, what we claim is:—

1. A device of the class described, comprising a member hooked at both ends to engage at one end under a plate and at the other end to overlie a rail base, and means to hold said hook member in position.
2. A device of the class described, comprising a member hooked at both ends to engage at one end under a plate and at the other end with a positioning and holding means, and a positioning means to be interposed between said second end and a rail base.
3. A device of the class described comprising a member hooked at both ends to engage at one end under a plate and at the other end with a holding means, a positioning means for said member and a key insertable between the second hooked end of the member and the positioning means.
4. A device according to claim 3, in which the positioning means is adapted for supporting engagement at its ends on said plate and on a rail base, respectively.
5. A device according to claim 3, in which the positioning means is adapted to be ten-

- sioned between its ends supported respectively on the plate and on a rail base, and the key.
6. A device of the class described, comprising an apertured clip adapted to rest at its ends on a rail base and rail support respectively, means engageable with the rail support passing through the clip aperture, and a key insertable between said means and the clip to hold the clip down on the rail support and rail base.
7. A device of the class described, for use with a rail and an apertured rail support, comprising a clip adapted to rest at its ends on the rail and the rail support respectively, and means insertable through the support aperture engageable with the under side of the support, and a key formed to be driven between the clip and said means to press the clip down on the rail and support.
8. A device of the class described, comprising a plate adapted to be supported at its ends, a hook member, and a key adapted to be driven between the hook member and the plate intermediate the ends thereof.
9. A device according to claim 8, in which the plate is apertured for passage of the hook member.
10. A device according to claim 8, in which the plate is apertured for reception of the hook member and its point whereby the hook will be held against opening under tension.
11. A device of the class described, comprising an apertured plate, a bar passing through the plate and bent upon itself to U-shape, the body and end of the bar being both located in the plate aperture, and a key driven between the bend of the bar and said plate.
12. A device of the class described comprising an apertured plate, a bar passing through the plate aperture and bent to provide a hook facing the plate, and a key driven between the plate and bar hook.
13. In combination with a device according to claim 12, an extension on said hook paralleling the bar and at its end entering the plate aperture, whereby the key is maintained in engagement with the hook.
14. A device of the class described, for use with a rail support, comprising, a plate formed to be supported at its ends on the support and on a rail respectively, a bar hooked at one end for attachment to the support and hooked at the opposite end for engagement with a key, and a key adapted to be driven between the second hooked end and the plate intermediate the ends thereof.
15. In combination with a device according to claim 14, an extension at the second hooked end of the bar to hold the key in place.
16. A device according to claim 14, in which the plate is apertured for passage of the bar, in combination with an extension at the second hooked end of the bar entering the plate aperture.
17. A device according to claim 14, in which the support is apertured for passage of the bar, in combination with means to hold the bar in hooking engagement with the support.
18. A device according to claim 14, in which the support is apertured for passage of the bar, in combination with means insertable in the support aperture to hold the bar in hooking engagement with the support.
19. A device according to claim 14, in which the first mentioned end of the bar is pointed for driving into soft material.
20. A device according to claim 14, in which the first mentioned end of the bar is pointed below the hook thereof and formed with an inclined surface adapted on lateral movement of the bar to urge the same upwardly.
21. A device according to claim 14, in which the key is notched in that edge engaging the bar hook and the bar hook formed for engagement in said notches to releasably lock the key.

In witness whereof, we have hereunto set our hands.

FRANCIS W. COOPER.
HENRY STEADWORTHY.

Certificate of Correction.

It is hereby certified that in Letters Patent No. 1,422,340, granted July 11, 1922, upon the application of Francis W. Cooper and Henry Steadworthy, of Montreal, Quebec, Canada, for an improvement in "Anchors and Clips for Rails and the like," errors appear in the printed specification requiring correction as follows: Page 1, line 17, strike out the word "tend", and line 18, after the word "rail" insert the words *under ordinary conditions*; page 3, lines 11 and 12, strike out the words "tends to hold the rail against the" and insert instead *is sufficient to hold the rail under ordinary conditions against the tendency to*; and that the said Letters Patent should be read with these corrections therein that the same may conform to the record of the case in the Patent Office.

Signed and sealed this 19th day of September, A. D., 1922.

[~~SEAL.~~]

WM. A. KINNAN,
Acting Commissioner of Patents.
